CLAIM

The ornamental design for an ear protection shield, as shown and described.

DESCRIPTION

FIG. 1 is a perspective view of an ear protection shield showing my new design;

FIG. 2 is another perspective view of FIG. 1, shown in a used condition with a human figure shown in broken lines;

FIG. 3 is a front view of FIG. 1;

FIG. 4 is a rear view of FIG. 1; and,

FIG. 5 is an enlarged portion view of encircled portion labeled, "5," in FIG. 1.

The dot-dashed broken lines shown in FIGS. 1 and 5 illustrate the boundary lines of the enlarged portion view of FIG. 5 and form no part of the claimed design. The even dashed broken lines shown in the drawing view of FIG. 2 of a human figure form no part of the claimed design.

All surfaces not shown form no part of the claimed design.
